UNITED STATES PATENT OFFICE.

FRANKLIN PIERCE BURNHAM AND JEFFERSON DAVIS ALSUP, OF
MIDDLETOWN, OHIO.

DESIGN FOR A BICYCLE CRANK-HANGER.

SPECIFICATION forming part of Design No. 31,098, dated June 27, 1899.

Application filed March 1, 1897. Serial No. 625,675. Term of patent 14 years.

To all whom it may concern:

Be it known that we, FRANKLIN PIERCE BURNHAM and JEFFERSON DAVIS ALSUP, citizens of the United States, residing at Middletown, in the county of Butler and State of Ohio, have invented and produced a certain new and useful Design for a Bicycle Crank-Hanger, of which the following is a description.

Our invention relates to a design for a bicycle crank-hanger and is illustrated in the accompanying drawing, wherein—

A indicates the cylindrical-shaped body of the hanger, and B the enlarged cap-like ends connected with the cranks.

The essential feature of our design is the 15 cylindrical-shaped body of the hanger with enlarged cap-like end portions to which the cranks are connected.

We claim—

The design for a bicycle crank-hanger herein shown and described. 20

FRANKLIN PIERCE BURNHAM.
JEFFERSON DAVIS ALSUP.
